UNITED STATES PATENT OFFICE.

ALEXIS E. BEZOIER, OF MINNEAPOLIS, MINNESOTA.

DISPLAY-CABINET.

1,264,602.

Specification of Letters Patent. Patented Apr. 30, 1918.

Application filed December 30, 1916. Serial No. 139,900.

To all whom it may concern:

Be it known that I, ALEXIS E. BEZOIER, a citizen of the United States, residing at Minneapolis, in the county of Hennepin and State of Minnesota, have invented certain new and useful Improvements in Display-Cabinets; and I do hereby declare the following to be a full, clear, and exact description of the invention, such as will enable others skilled in the art to which it appertains to make and use the same.

My invention has for its object to provide an improved cabinet with movable racks, adapted for use in displaying various articles of merchandise, but especially adapted for use in displaying hats.

To the above end, generally stated, the invention consists of the novel devices and combinations of devices hereinafter described and defined in the claims.

In the accompanying drawings, which illustrate the invention, like characters indicate like parts throughout the several views.

25 Referring to the drawings:

Figure 1 is a side elevation of the improved cabinet with one of its side panels removed to expose the interior of the cabinet and also showing the doors open;

30 Fig. 2 is a fragmentary vertical section taken on the line 2—2 of Fig. 1;

Fig. 3 is a plan view of one of the upper track sections;

Fig. 4 is a view in a horizontal section 35 taken on the line 4—4 of Fig. 1, with the doors closed and illustrated in open positions by means of broken lines; and,

Fig. 5 is a side view of one of the display racks.

40 The numeral 1 indicates a rectangular cabinet having a pair of horizontally swinging doors hinged thereto. It will be noted that these doors 2 terminate considerably short of the top and bottom of the cabinet 45 and have panels 3 of glass. If desired, these panels may be mirrors, so that a prospective purchaser may observe the appearance of hats while standing in front of the cabinet.

Within the cabinet 1, as shown, are four 50 display racks 4. These display racks 4 are identical one with the other and a description of the one will suffice for the other. Each display rack 4 comprises top, bottom, back and side members, rigidly connected in a rectangular arrangement, and a plurality of shelves 5. The shelves 5, as shown, are

each formed by a plurality of horizontally spaced rods having their ends secured to the side members of the rack. Any other desired form of shelving, of course, may be substituted for the shelving shown. A long vertical slot 6 is cut in each side member of the display rack 4 and extends from the top thereof, downward substantially two-thirds of the full height of said rack. On the outer 60 face of each side member of the rack 4 are upper and lower pairs of grooved wheels 7 and 8, respectively. The foremost upper wheel 7 and the wheels 8 are all located in the same vertical plane and journaled directly to the respective side of the rack 4. The rearmost wheel 7 for a purpose that will presently appear is located in a vertical plane outward of the other wheel 7 and is journaled to a bracket 9, secured to the display 70 rack 4.

The display racks 4 are mounted to travel an endless rectilinear course in a vertical plane that transversely intersects the cabinet 1 and are moved successively in front of the 80 door opening thereof. During the vertical movement of the racks 4, at the front of the cabinet 1, the foremost wheels 7 and 8 thereof run on vertical track sections 10, secured to the inside of the front of the 85 cabinet 1 between the door opening and the side panels thereof. The lower ends of the track sections 10 are curved downward into horizontal track sections 11 which form continuations thereof, and on which track sections 90 11 the wheels 8 travel and support racks 4, when in their lowermost positions and moving horizontally from the front to the rear of the cabinet 1. The rear ends of the track sections 11 are curved upward into 95 vertical track sections 12 which form continuations thereof, and are secured on the back of the cabinet 1. The rearmost wheels 8 travel on the track sections 12 during the upward vertical movement of the racks 4 at 100 the back of the cabinet 1. During this movement of the racks 4 the offset wheels 7, journaled in the brackets 9, run on track sections 13, which extend parallel to the track sections 12 and are secured to the back of the 105 cabinet 1. While the racks 4 are moving from the back to the front of the cabinet 1, during their uppermost traveling movement, the foremost wheels 7 travel on track sections 14 and the rearmost of said wheels 110 travel on track sections 15. Each pair of track sections 14 and 15 is secured or formed

2
on the upper face of a bar 16 rigidly secured in the cabinet 1. Passageways 17 and 18 are formed in the vertical faces of the bars 16 at the ends of the track sections 14 and 15, respectively. These passageways 17 and 18 afford clearance for the wheels 7 during the elevating and lowering movements of the racks 4, to and from the track sections 14 and 15.

10 In order that the wheels 7 may have a continuous track to travel on, during the movement of the racks 4, from the back to the front of the cabinet, it is necessary to laterally offset said wheels, with respect to each other, and provide a double track therefor. With a single track, it would, of course, be necessary to form a gap therein for the passage of the forward wheel 7 there-through, during the lifting movement of the 20 racks 4, and to form a second gap therein for the passage of the rear wheel 7 there-through, during the lowering movement of said racks.

Transfer bars 19 and endless sprocket chains 20 are provided for moving the display racks 4 horizontally in pairs, one above the other, and for successively moving alternate pairs of said racks vertically. During the horizontal movement of the 30 racks 4 the upper pair thereof is moved on the track sections 14 and 15 from the back toward the front of the cabinet 1, and the lower pair of said racks is moved on the track sections 11 from the front to the rear of said cabinet. As previously stated, the display racks 4 are moved vertically in alternate pairs, that is, while one pair is moving the other pair is standing still and located, the one above the other, at the 40 center of the cabinet 1 and between said two moving racks. While one of the racks 4 is moving vertically downward at the front of the cabinet 1 with its foremost wheels 7 and 8 running on the track sections 45 10, the other of said moving racks is moving upward at the back of the cabinet, with its rearmost wheels 7 and 8 running on the track sections 12 and 13. During the vertical movements of the front and rear racks 50 4 certain of their grooved wheels 7 and 8 are held on the track sections 10, 12 and 13 by the engagement of said moving racks with the stationary and centrally located racks.

55 The sprocket chains 20 travel in vertical planes between the sides of the racks 4 and the side panels of the cabinet 1. Each sprocket chain 20 runs over a pair of horizontally spaced sprocket wheels 21 journaled on a bar 22 and under a pair of horizontally spaced sprocket wheels 23 journaled on a bar 24. The bars 22 and 24 are rigidly secured in the cabinet 1 slightly below the tops of the doors and slightly 65 below the lower ends thereof, respectively.

Each set of sprocket wheels 21 and 23 keeps the respective sprocket chain 20 in rectilinear arrangement, except at the centers of its horizontal runs where the same is looped downward between upper and lower pairs 70 of sprocket wheels 25 and 26, respectively. These sprocket wheels 25 and 26 are journaled, respectively, on the bars 22 and 24. The upper loop of each sprocket chain 20 runs under a sprocket wheel 27 journaled on 75 a bar 28, and the lower loop in said chain runs under a sprocket wheel 29 journaled on a bar 30. The bars 28 and 30 are rigidly secured in the cabinet 1.

The transfer bars 19 are vertically disposed and there is one at each side of each rack 4. The lower ends of the transfer bars 19 are pivoted at 31 to the sprocket chains 20, and their upper ends are connected to the racks 4 for pivotal and vertical 85 sliding movements by providing the same with laterally projecting bolts 32 which work in the slots 6. The extreme upper ends of the transfer bars 19 above the bolts 32 are in the form of wedges 33, adapted to 90 enter V-shaped notches in shoulders 34 secured to the upper ends of the racks 4 and span the slots 6.

The intermittent movement imparted to each rack 4 by the respective transfer bars 95 19 carried by the continuously moving sprocket chains 20 is as follows, to wit:—

During the lower movement of the foremost rack 4, the same is supported from its shoulders 34 on the upper ends of the respective transfer bars 19 and, upon reaching its lowermost position, the wheels 8 thereof are carried onto the track sections 11. From this position of the rack 4, the same is moved on the track sections 11, during the movement of the transfer bars 19, between the foremost sprocket wheels 23 and 26. As the transfer bars 19 pass over the foremost sprocket wheels 26, the same are withdrawn from engagement with the 11 shoulders 34 and leave the rack in an intermediate position in which it remains, while said transfer bars 19 are traveling the courses of the lower loops in the chains 20. As the transfer bars 19 move over the rear-most sprocket wheels 26, the transverse bars 19 are again carried into interlocking engagement with the shoulders 34 and move the rack 4 on the track sections 11 to the 12 rear of the cabinet. While the transfer bars 19 are moving from the rear-most sprocket wheels 23, the rack is lifted thereby from its lowermost to its uppermost position. During this movement of the rack 4, the foremost wheels 7 pass through the passageways 17 and the rearmost wheels 7 move through the passageways 18. As the transfer bars 19 start on their horizontal movement toward the front of the cabinet, the foremost wheels 7 are carried onto the track 13

sections 14 and the rearmost wheels 7 are carried onto the track sections 15. With the wheels 7 on the track sections 14 and 15, the rack 4 is moved toward the front of the cabinet, while the transfer bars 19 are moving between the rearmost sprocket wheels 21 and 25. The transfer bars 19, in passing over the rearmost sprocket wheels 25, are again withdrawn from the shoulders 34 and leave the rack 4 in an intermediate position, while said transfer bars 19 are traveling the courses of the upper loops in the chains 20. At the completion of these courses, the transfer bars 19 are again carried into interlocking engagement with the shoulders 34 and continue the movement of the rack 4 on the track sections 14 and 15 to a position where the wheels 7 are in registration with the respective passageways 17 and 18. From this position of the rack 4, the same is lowered past the door openings, during the movement of the transfer bars 19 from the foremost sprocket wheels 21 to the lowermost sprocket wheels 23, which completes the circuit of one of the racks 4.

As one means for moving the racks 4 successively past the door openings in the cabinet 1, there is provided a motor 35, diagrammatically illustrated in Fig. 2, and connected by any suitable means to a shaft 36 on which the rearmost sprocket wheel 21, on one side of the cabinet, is keyed. The expression "upper and lower," with respect to the tracks and the depending loops in the chains 20, is used for the sake of definiteness and it is, of course, understood that the cabinet and the mechanism therein may be designed, so that the display racks will move in a horizontal plane.

The above described display cabinet is, as is evident, designed to hold a large number of hats or other articles of merchandise and, by setting the display racks in motion, by the motor shown in the drawings or other suitable means, said display racks are moved successively before a prospective buyer.

In place of using metal rods for shelving, as shown, it is, of course, understood that strips of canvas or other fabric may be substituted therefor. Fabric shelving has one important advantage over shelving that has a hard surface and that is, it will conform to all shapes of hats and prevent them from losing their shape.

55. What I claim is:—

1. The combination with a cabinet, of a plurality of racks mounted in the cabinet for movement in an endless course, and continuously moving means for intermittently and simultaneously individually moving all of the racks and for intermittently moving alternate racks.

2. The combination with a cabinet, of a plurality of racks mounted in the cabinet for movement in an endless course, and con-

tinuously moving means for intermittently and simultaneously individually moving said racks in two groups, the one past the other and in opposite directions, and for intermittently moving alternate racks in opposite directions. 70

3. The combination with a cabinet, of a plurality of racks mounted in the cabinet for movement in an endless course, a driven belt, wheels journaled in the cabinet for guiding the belt, and transfer bars permanently connecting the racks to the belt and arranged to intermittently move said racks in their endless course. 75

4. The combination with a cabinet, of a plurality of racks mounted in the cabinet for movement in an endless course, a driven belt, wheels journaled in the cabinet for guiding the belt, and transfer bars carried by the belt and connected to the racks for sliding movement and arranged to impart intermittent movement to the racks in their endless course. 80

5. The combination with a cabinet, of a plurality of racks mounted in the cabinet for movement in an endless course, a driven belt, wheels journaled in the cabinet for guiding the belt, transfer bars carried by the belt and connected to the racks for sliding movement, and means with which the transfer bars intermittently engage to hold the same on the racks against sliding movement in one direction. 90

6. The combination with a cabinet, of a plurality of racks mounted in the cabinet for movement in an endless course, a driven belt, wheels journaled in the cabinet for guiding the belt, transfer bars pivoted to the belt and connected to the racks for pivotal and sliding movements, and means with which the transfer bars intermittently engage to hold the same on the racks against pivotal movement and sliding movement in one direction. 100

7. The combination with a cabinet, of a plurality of racks mounted in the cabinet for movement in an endless rectilinear course, a driven belt, wheels journaled in the cabinet for guiding the belt in a rectilinear course and for holding opposite runs of the belt looped, transfer bars carried by the belt and connected to the racks for sliding movement while said belt is moving through the loops in its course, and means for intermittently securing the transfer bars to the racks against sliding movement in one direction. 110

8. The combination with a cabinet, of a plurality of racks mounted in the cabinet for movement in an endless rectilinear course, a driven belt, wheels journaled in the cabinet for guiding the belt in a rectilinear course and for holding the upper and lower runs of the belt to form depending loops, upper and lower tracks in the cabinet, transfer bars carried by the belt and having sliding engagement with the racks, and stops on the 115 120 125 130

racks with which the transfer bars engage to carry the racks to and from said tracks and for intermittently moving the racks horizontally on the tracks.

9. The combination with a cabinet, of a plurality of racks mounted in the cabinet for movement in an endless rectilinear course, a driven belt, wheels journaled in the cabinet for guiding the belt in a rectilinear course and for holding the upper and lower runs thereof to form depending loops, upper and lower tracks in the cabinet, transfer bars pivoted to the belt at one of their ends and

having their other ends connected to the racks for pivotal and sliding movements, and 15 stops on the racks with which the transfer bars engage at the limit of their sliding movement and lock the same against pivotal movement with respect to the racks.

In testimony whereof I affix my signature 20 in presence of two witnesses.

ALEXIS E. BEZOIER.
